UNITED STATES PATENT OFFICE.

WILLIAM F. MICHAEL, OF PHILADELPHIA, PENNSYLVANIA, ASSIGNOR TO
BAILEY, BANKS & BIDDLE, OF SAME PLACE.

DESIGN FOR A SPOON.

SPECIFICATION forming part of Design No. 21,127, dated October 20, 1891.

Application filed July 9, 1891. Serial No. 398,977. Term of patent 3½ years.

To all whom it may concern:

Be it known that I, WILLIAM F. MICHAEL, a citizen of the United States, residing in the city and county of Philadelphia, State of Pennsylvania, have invented and produced a new and original Design for a Spoon, of which the following is a specification, reference being had to the accompanying drawing, forming part thereof.

The leading feature of my design for a spoon is the handle, having on the tip thereof the representation of a grouping of canteens, each with a bust of a man thereon.

In the drawing, A designates the handle of a spoon, on the tip of which is the representa-

tion of a grouping of canteens B, having on the faces thereof, respectively, the busts of Generals Grant, Sherman, and Sheridan.

The shank and bowl shown form no part of the present design, the novel feature of the latter being embodied in the tip.

I claim—

The design for the tip of a spoon, the same consisting of a tip having thereon a grouping of canteens, each with the bust of a man on the face thereof, as shown and described.

WILLIAM F. MICHAEL.
